DESIGN FOR A DISPLAY CABINET

Carleton Male, Flushing, N. Y., assignor to Sloane-Blabon Corporation, a corporation of Delaware

Application May 12, 1948, Serial No. 146,319

Term of patent 14 years

(Cl. D80—11)

To all whom it may concern:

Be it known that I, Carleton Male, a citizen of the United States, residing at Flushing, in the county of New York and State of New York, have invented a new, original, and ornamental Design for a Display Cabinet, of which the following is a specification, reference being had to the accompanying drawing, forming part thereof.

I claim:

The ornamental design for a display cabinet, as shown.

CARLETON MALE.
